United States Patent Office

Des. 211,105
Patented May 21, 1968

211,105

TUMBLER OR THE LIKE

Raymond Swenson, 109 W. School St.,
Grayslake, Ill. 60030

Filed Oct. 17, 1967, Ser. No. 9,026

Term of patent 14 years

(Cl. D36—8)

FIG. 1

FIG. 2

FIG. 3

FIG. 1 is a perspective view of a tumbler or the like showing my new design.

FIG. 2 is a side elevational view thereof.

FIG. 3 is a transverse sectional view taken along line 3—3 of FIG. 1.

I claim:

The ornamental design for a tumbler or the like, substantially as shown.
